UNITED STATES PATENT OFFICE.

THOMAS F. SEERY, OF BOSTON, MASSACHUSETTS.

DUMPING-CAR.

SPECIFICATION forming part of Letters Patent No. 323,744, dated August 4, 1885.

Application filed April 30, 1885. (No model.)

To all whom it may concern:

Be it known that I, THOMAS F. SEERY, of Boston, in the county of Suffolk and State of Massachusetts, have invented certain new and 5 useful Improvements in Dumping-Cars, of which the following is a full, clear, and exact description.

This invention, in substance, consists, first, of a dumping-car which has its body adapted 10 at each of its four sides to be opened and closed, and arranged upon its truck or support to be upset in direction of either of its sides, adapted to be opened and closed for the dumping of its contents at said side, first having opened the same, and to be secured against 15 accidental upsetting; second, of a dumping-car which has its body adapted to be opened and closed at its sides and to be upset in the direction of either of its so opening and closing sides, and arranged upon its truck or support to be adjusted in height in relation thereto, and as so adjusted secured against accidental displacement, as also secured against 20 accidental upsetting; third, of a dumping- 25 car which has its body adapted to be opened and closed at either side or at two or more or all of its sides, and is provided with fastenings for holding the so adapted opening and closing side or sides closed and against accidental opening when the same is closed, and 30 which fastening is adapted to be operated to secure and release the so adapted opening and closing side to which it is applied and from and at the side or part of the car-body which 35 is opposite thereto.

In the drawings the present improvements in dumping-cars are illustrated. Figure 1 is a side elevation with the car-body in its normal position and there secured. Fig. 2 is an 40 end elevation with the car-body upset or dumped at one side of the car. Fig. 3 is a plan view of the truck or support of the car-body with the body detached. Fig. 4 is a plan or face view of the under side of the car-body. 45 Figs. 5 and 6 are views in detail, hereinafter referred to.

In the drawings, A represents the body of a dumping-car, B its truck or support, and C its four wheels, all of which, except as to the 50 features of this invention, are the same as ordinary. The body B is made of square shape,

and it consists of a bottom, D, four sides, E, and four corner-posts, F. Each side E of the body is suspended by loops or eyes *a*, attached to its upper edge upon and from a separate 55 rod of the four horizontal metal rods *b*. The several rods *b* join the corner-posts F of the car-body, and, passing through the posts, are attached thereto by screw-nuts *d*, applied to them on opposite sides of and jammed against 60 the posts. The sides E of the car-body, suspended as described, are thus capable of being swung on said rods *b* to be opened and closed, and, closed, they fit between the corner-posts F, and are there held against accidental opening by means of a button or flat-shaped fastening-plate, *f*—a separate one for 65 each side. Each button-fastening *f* has a knob, *g*, for convenience in operating or handling it, and the fastenings on the two sides of the body 70 which are opposite to each other are attached to a common operating-rod, *h*, which extends horizontally across and under the bottom D of the car-body, and turns in suitable supports and bearings thereof.

The two button-fastenings *f* of each operating-rod *h* are at the opposite ends thereof, and they are situated in lines running at an angle to each other and on opposite sides of the axis of rotation of their rod *h*, and all so 80 that by rotating said shaft both of said button-fastenings not only can and will be placed in position to fasten and hold closed the sides of the car to which they are applied, but also can and will be placed, the one in a position 85 to hold its side of the car-body closed, and the other in position to allow its side of the car-body to be opened.

The operating-rod *h* for the button-fastenings can be worked from either of its ends, 90 and thus the side of the car at which it is intended to dump the contents of the car can be released by operating its fastenings from the side of the car opposite thereto.

G is a vertical metal loop or eye attached 95 to the center of the car-body, and engaged with and hung upon and crossing a vertical metal loop or eye, H, at the upper end of a vertical square-shaped standard, J, which is located and fits loosely within a corresponding shaped vertical socket, K, of the car truck or support, and is secured in said socket by 100

transverse bolts *k*, which pass loosely through holes *l* in the vertical walls of said socket and holes *m* in said standard *J*, and at one end are headed, and at the other end have a screw-nut, 5 *n*, applied to them. This loop attachment of the car-body to its truck or support *B* enables the body to be upset and dumped in a direction toward either side thereof, or, in other words, in lines or directions practically at 10 right angles to each other.

15 *L* are chains, each hung at one end to the eye *g* of a vertical and adjustable screw-eye, *r*, screwed into the bottom of the car-body and midway of the length of each of its sides. The lower end of the chain is connected to a metal cross-bar, *t*, and each bar is fastened by 20 an attachable and detachable pin, *u*, that is entered into a socket, *v*, suitable to receive it, of the sides of the car-truck. This chain-and-pin connection between the car body and truck which is at either side thereof, when the several holding-pins *u* are inserted in their respective sockets of the truck, each chain being of a suitable length thereof, holds the car-body from upsetting in the direction of either 25 of its sides.

30 Removing a holding pin, *u*, at either side of the car-truck sets the car-body free to be upset only in a direction toward the side thereof which is opposite to the side having the chain-holding pin so released, and to the so upsetting of the car-body the other attached and connected chains *L* offer no obstruction.

35 The standard *J*, to which the car-body is hung by metal loops *G H*, and which is secured in its receiving-socket *K* of the car-truck by horizontal cross rods *k*, as described, (two bolts being preferable,) has a series of 40 receiving-holes, *m*, through it for said bolts, placed at different heights, and thus the car-body can be adjusted and fixed as to its height relative to its support as may be desired or required for the best and most convenient 45 dumping of different materials with which the car may be loaded—as, for instance, gravel, clay, &c. When this adjustment of the car-body as to height is made, the chain-connections *L* of the car-body must be adjusted accordingly, and this can be accomplished in 50 the arrangements thereof shown by turning the screw-eyes *r*, connecting them to the car-body, into or out of said body, as the case may require, turning them in shortening and 55 turning them out lengthening to that extent the chains *L*. These screw-eyes *r* preferably screw into screw-nuts *W*, set in the wood-work of the bottom of the car-body.

Again, other forms of flexible connection 60 between the car-body at each side thereof and its truck may be used in lieu of the chain-connection described—as, for instance, a rope; and the sides of the body may be arranged for being opened and closed in other ways than 65 the way particularly described and shown—as, for instance, to slide up and down in suitable guideways of the corner-posts *F*. Other

fastenings for the sides of the car-body may be used in place of the swinging buttons *f* described.

70 A dumping-car having in substance all the features of construction and arrangement of parts herein described contains obvious advantages, and plainly is most efficient, practical, and useful.

75 Having thus described my invention, I claim—

1. A dumping-car having a body with four opening and closing sides, and supported upon the truck or other suitable support of the car 80 only at its center, and to be tilted thereon in the direction of either its said four opening and closing sides, in combination with means, substantially as described, to fasten and hold the body at each of its sides against accidental 85 tipping, and released on either side to permit the body to be tipped only in the direction of the side opposite thereto, substantially as described, for the purpose specified.

2. A dumping-car having a body with one 90 or more opening and closing sides, attached to the truck or suitable support of the car, to be tilted thereon in the direction of either of its said opening and closing sides, and said support for the body constructed and arranged to 95 be adjusted vertically independently of the tilting of the body, substantially as and for the purposes described.

3. A dumping-car having opposite sides of its body adapted to be opened and closed, in 100 combination with fastenings applied to each of said opening and closing sides, and carried by a common operating-rod arranged for the fastening of either of the so opening and closing sides, to be operated through its said rod 105 at the side of the car directly opposite to such fastening, substantially as described, for the purpose specified.

4. A dumping-car having a body with three 110 or more opening and closing sides, *E*, and centrally suspended by a vertical loop or eye, *G*, from a vertical loop or eye, *H*, of the truck or other suitable support of the car, so that it can only upset in directions or lines practically 115 at right angles to each other, and is incapable of rotation upon its said support, in combination with devices adapted to fasten the body against accidental upsetting, substantially as described, for the purpose specified.

5. The dumping-car having one or more of 120 the sides of the body adapted to be opened and closed, and the body attached to a standard, *J*, to be upset in the direction of either of its opening and closing sides, which standard is provided with a series of holes, *m*, arranged 125 in a vertical socket, *K*, of the truck or other body support of the car, in combination with rods *k*, which pass loosely through the holes *m* of said standard and the holes *l* of the walls of said socket, and are secured in place, substantially as described, for the purpose specified.

130 6. A dumping-car having opposite sides adapted to be opened and closed, in combina-

tion with button-fastenings, *f*, for each of said opposite sides, attached to a common operating-rod, *h*, turning in suitable bearings of the car-body, substantially as described, for the 5 purpose specified.

7. A dumping-car having one or more of the sides of its body adapted to be opened and closed, and the body arranged upon its truck or other support therefor of the car, and 10 otherwise adapted to be upset in the direction of either of its said opening and closing sides, and to be adjusted in height, and secured at

its so adjusted height, in combination with flexible connections between the sides of the body and its support or truck, adapted to be 15 lengthened and shortened, substantially as described, for the purpose specified.

In testimony whereof I have hereunto set my hand in the presence of two subscribing witnesses.
